UNITED STATES PATENT OFFICE.

JOHN J. BURK, OF BUFFALO, NEW YORK, ASSIGNOR OF ONE-HALF OF HIS
RIGHT TO E. M. JEWETT, OF SAME PLACE.

MACHINE FOR DRIVING NAILS.

SPECIFICATION forming part of Letters Patent No. 231,475, dated August 24, 1880.

Application filed June 2, 1880. (Model.)

To all whom it may concern:

Be it known that I, JOHN J. BURK, a subject of the Queen of Great Britain, residing in Buffalo, in the county of Erie and State of New York, have invented certain new and useful Improvements in Machines for Driving Nails, of which the following is a specification.

The object of my invention is to provide a machine for automatically feeding and driving 10 nails into hoops, cheese or other boxes, and clinching them when required.

The first part of my invention relates to the devices for holding and feeding the nails; and it consists of a hollow drum or barrel set in 15 suitable bearings, so as to turn easily, and having openings through which the nails drop into a trough having a long narrow opening through the bottom, in combination with a vibrating plate having openings for receiving, separating, and dropping the nails, one at a time, into 20 a spout which delivers them to the nail-driver.

The object of the second part of the invention is to produce a simple nail-clinching device; and it consists in the combination, with 25 the nail-driving bar, of an oscillating block (held in position by a spring) through which the nail passes while being driven through the article to be nailed against the clinching-bar, the arrangement being such that the point of 30 the nail is directed upward or in the direction it is intended the nail should clinch while being driven, as will be more clearly hereinafter shown.

The third part of my invention also relates 35 to the nail-driving apparatus; and it consists in the combination, with the nail-bar, of an adjusting-nut provided with a vulcanized rubber back for the purpose of regulating the pressure of the driver against the nail, all of 40 which will be more clearly understood by reference to the drawings, in which—

Figure 1 is a vertical longitudinal section through the machine in line $\bar{X} X$, Fig. 2. Fig. 2 represents a plan or top view of the machine. Fig. 3 is partly a front and top view of the nail-drum, nail-troughs, nail-conveyers, and the nail-separating device. Fig. 4 is a portion of the nail-separating device and conveyer. Fig. 5 is a portion of one of the nail-conveyers, showing the arrangement of the 50 nails as they move down the incline through

the narrow openings in said conveyers. Fig. 6 represents a section through the nail drum or receptacle on line Y, Fig. 3. Fig. 7 is a detached view, showing a vertical longitudinal section through the nail-driver. Fig. 8 is a front view of the nail-driver. Fig. 9 represents a portion of the rear part of the nailing device, showing the adjusting-nut and its rubber washer or back; and Fig. 10 is a front 60 view of a portion of the conveyers, the cross-bar or support below them, a part of the separating-bar, and also an end view of one of its supporting-arms.

In said drawings, A represents the frame of 65 the machine, supported on legs A' and strengthened by braces or cross-bars A² A³.

B is the nail-drum. It is provided with the long narrow openings B' for the nails to drop through when the machine is in operation, and 70 a door, B², made and hinged thereto in the ordinary way, (see Fig. 6,) through which the nails are passed when filling it. This drum or barrel B is supported in bearings B³ in the vertical supports or posts C, so as to turn 75 easily. (See Fig. 3.) It receives a partial rotary movement back and forth by means of the cord or chain C', weight C², and foot-lever C³, said cable or cord being connected to the weight C², as shown in Fig. 1, and passed once 80 or twice around the nail-drum B, and from thence down under the nail-feeding apparatus at D, then over the curved nail-driving bar P and down to the foot-lever C³, to which it is connected at D².

It will be seen by reference to Fig. 1 that a movement of the foot-lever C³ downward by the foot will draw the cord C' downward and forward, thereby causing the drum or nail-holder B to turn in the direction of the arrow 90 and the weight C² to move upward, and that when the pressure of the foot is taken off from said lever the weight C² will descend and cause the nail-holder to turn back or in the opposite direction.

The nail-troughs E are placed under the drum B, so as to catch the nails as they drop therefrom. E' (see Fig. 3) is a thin or narrow opening at the bottom of the troughs, which extends along their whole length, and to the 100 end of the conveyers E² both are inclined, so that as the nails drop in they pass through

said opening except the heads, which are too large to pass through, and they consequently fall into the position shown in Fig. 5. The troughs and conveyers are inclined sufficiently 5 to allow the nails, as they drop into the openings E', to slide down easily until they are stopped by the nail-separating bar E³, which is held in place by two arms, F', pivoted to it at F², and to the under parts of the troughs 10 about F, so that the bar can swing back and forth in the direction of the arms G G'. It is represented in Fig. 3 as broken in three parts, the part at G² showing it in position for separating one nail from another, the part G³ showing 15 the opening g in said bar at its farthest point in the direction of the arrow G', and the part G⁴ showing the position of said opening g (or openings g) when the bar has reached the limit of its movement in the direction of the 20 arrow G.

The openings in the conveyer or slideways E² terminate in a larger opening, H, (see Figs. 3 and 4,) through which the nails drop as they are brought into position by the separating-bar E³, as above mentioned, into the spouts 25 H'. (See Figs. 1 and 7.)

The bar E' receives its vibrating movements one way by a spring, K, (see Fig. 3,) and the other way by means of the foot-lever C³, weight 30 J, and a cord, H², fastened to said lever by a joint, I, (see Fig. 1,) which cord is then passed downward and is fastened to the weight J, and to said weight is fastened another cord or its equivalent, I', which cord passes up over a pulley, J', on the cross-bar J², under the conveyers 35 or slideways, a front view of which is shown in Fig. 10, and after passing horizontally a short distance, as shown, the said cord or chain is firmly fastened to a pin or bolt, J³. It will be 40 seen that a movement of the foot-lever C³ downward will cause the cord H², which passes easily through the loop or eye I², to draw the weight J upward, which operation allows the spring K to act and move the arms F' and 45 plate or bar E³ in the direction of the arrow G, (see Fig. 3,) and that a reverse movement of the foot-lever C³ will allow the weight J to act and move the said bar E³ in the opposite direction.

50 To the shaft K' is securely fastened two outside cranks, K², one on each side of the machine, to which the connecting-rods L are jointed in the ordinary way, the opposite ends of said rods being jointed to the nail-driving-bar carriage L', which carriage is supported by and slides forward and back on the rods L².

To the shaft K' is rigidly fastened a crank, M, having a connecting-rod, i, jointed thereto, as shown in Figs. 1 and 2, and having its opposite end jointed to the foot-lever C³ by a bolt or pin, D², or in any other well-known way.

65 It will now be seen that a movement of the foot-step C³ downward will draw the crank M also downwardly by means of the connecting-rod i, which operation will turn the shaft K' in the same direction, and also the cranks K²,

and thereby draw the connecting-rods L and the nail-driving-bar carriage forward.

The backward or reverse movement of said 70 carriage is produced by the weight C², which is heavy enough to draw the foot-lever C³ up again by means of the cord or cable C', as hereinbefore mentioned.

The nail-driving bar N is supported at its 75 back end by the angular bar a, (which is rigidly fastened to the carriage L',) through the upright portion of which bar a it passes and is fastened by a rivet-head or washer, a'. It is also provided with a nut, N', and a vulcanized rubber washer, N². The object of the nut N' is to adjust the distance the bar N shall be moved forward, and the rubber washer allows it to adjust itself to any articles to be nailed 80 which may vary a little in thickness.

The forward end of the nailing-bar N passes into and through the nail-receiving box O, which box is provided with an opening, O', to receive the nails from the spouts H'. (See Fig. 7.) The boxes O are rigidly fastened to a cross-bar or carriage, P, which carriage is supported and also slides back and forth on the bars or rods L², and is fastened by chains P' to the carriage L'. (See Figs. 1 and 2.) Its backward and forward movements are produced by the 90 foot-lever W', which is connected by a rod, b, to the lower or horizontal end of an angular arm, c, the said arm being fitted on the shaft K', so as to turn easily thereon.

To the upper or vertical part of the arm c 95 is jointed a connecting-rod, f, having its opposite end securely fastened to the carriage P. (See Figs. 1 and 2.) Its object is to bring the nail-boxes forward, so as to hold the articles to be nailed firmly between them and the 100 clinching-bar.

It is obvious that a downward movement of the foot-lever W' will move the carriage P forward, and that a reverse movement will move it backward.

110 In the front end of the nail-box O is a cavity, into which is fitted a small block, Q. (See Figs. 7 and 8.) It has an opening, R, through it of the same size as the bore r of the box O, through which the nail-driving bar passes, 115 and is held to the box O by a rubber band or other equivalent spring, R'. The block Q, being of a slightly-sharper angle than the recess in which it is fitted, as shown in Fig. 7, and being held closely in place by the rubber 120 spring R', is capable of a vibratory movement, the upper inner corner or edge acting as a fulcrum, on which it rocks. In its downward position the opening R is exactly in line with the bore r. In its upward position the opening R 125 inclines upward a little, as shown in Fig. 7.

T represents the clinching-bar, against which the points of the nails turn while being driven. It is rigidly fastened to the frame of the machine by shortposts V, (see Fig. 1,) which bring 130 it to the proper height. The forward ends of the rods or bars L² pass through and are held by the posts V, as will be understood by reference to Figs. 1 and 2. The back ends, which

pass through the supports C, as shown in Fig. 1, are secured by a nut, V'.

It will be noticed that the carriages L' and P and clinching-bar T are in the form of a curve, and that the nailing apparatus is arranged to correspond, so that hoops or cheese-boxes may be nailed thereby; but they may be made straight, and the nailing devices may be arranged at right angles thereto, so that ordinary straight-sided boxes may be nailed. In that case what is used as a clinching-bar for articles requiring it may be made movable and adjustable, so as to be used as a gage, against which the box to be nailed is set and held in place, as in such boxes it is not necessary to clinch the nails.

The object of the chain P' is to prevent the carriage P from being drawn far enough from L' to draw the nail-driving bar out of place. They can be easily removed at any time when required.

The operation of my invention is as follows: The nail-holder being supplied with nails of the required size, a movement of the foot-lever upward and down will cause some of the nails to drop into the troughs and slide down the conveyers against the nail-separating bar E³, in the manner hereinbefore mentioned. A movement of the foot-lever C³ upward will now cause the separating-bar E³ to separate a nail and allow one to drop in each spout, from which it slides into a nail-box, O, as specified. The hoop or other article to be nailed is now placed between the clinching-bar and the nail-boxes O, and the foot-lever W' is forced down, which brings the nail-boxes forward and clamps the hoop firmly between them and the clinching-bar T. The foot-lever C³ is now forced down, thereby moving the carriage L' and nail-driving bar N forward, and driving and clinching the nail. The nail, in being driven, when it strikes the clinching-bar, bends upward, substantially as shown by the dotted lines Z in Fig. 7. The inclined opening of the block Q, through which the nail passes, causes it to bend in the direction of the incline.

Of course it will be seen that the opening of

the block Q comes into line with the bore r when the bar N passes through it in driving a nail, and that the spring R' causes it to move again into the position shown in Fig. 7 as soon as the bar N draws back out of it.

I claim as my invention—

1. The rotary nail-holder B, one or more inclined troughs and conveyers, E E², provided with the openings E', in combination with a nail-separating bar, E³, having openings g, and arranged to move at right angles to openings E', substantially as specified, for the purpose of separating the nails one at a time and dropping them into a suitable receptacle, as described.

2. In a nail-driving-machine, the combination of the nail-driver N, nail-box O, and perforated vibrating block Q, for the purpose of driving the nail and controlling the direction in which it shall bend in clinching, as specified.

3. In a nail-driving machine, the combination of the carriage P, nail-boxes O, clinching-bar T, angular arm e, foot-lever W', and the connecting rods or bars b f, for the purpose of clamping the article to be nailed.

4. The combination of the foot-lever C³, connecting-rod i, crank M, rigidly fastened to the shaft K', cranks K², also fastened to said shaft, connecting-rods L, and carriage L', provided with holding-bars a, for the purpose of giving the nail-driving bar N its proper movements, as herein set forth.

5. The combination of the foot-lever C³, cord or cable C', drum or nail-holder B, and weight C², for the purpose of operating the nail-holder of a nail-driving machine, substantially as described.

6. The foot-lever C³, cord H², passed through the loop or eye I² and connected with the weight J, as specified, in combination with the cord or cable I', pin or pulley J', and the nail-separating bar E³, as and for the purposes described.

JOHN J. BURK.
